DESIGN FOR A GRAND PIANO

Everett Worthington, Scarsdale, N. Y., assignor to
Story & Clark Piano Company, Chicago, Ill., a
corporation of Delaware

Application February 8, 1938, Serial No. 74,969

Term of patent 7 years

To whom it may concern:

Be it known that I, Everett Worthington, a citizen of the United States and resident of Scarsdale, in the county of New York and State of New York, have invented a new, original, and ornamental Design for a Grand Piano, of which the following is a specification, reference being had to the accompanying drawing, forming a part thereof.

Fig. 1 is a top plan view of the grand piano, showing my new design; and

Fig. 2 is a side elevational view thereof.

Fig. 3 is an enlarged fragmentary edge view of the top portion of the piano; and

Fig. 4 is a fragmentary vertical sectional view of the edge portion shown in Fig. 3, on line 4—4 in Fig. 3 of the drawing.

The dominant features of the design are shown in solid black lines.

I claim:

The ornamental design for a grand piano, as shown and described.

EVERETT WORTHINGTON.
